LADDER

Clayton E. Larson, 80 Moultrie St., Brooklyn, N.Y.

Filed Dec. 7, 1960, Ser. No. 63,147

Term of patent 14 years

(Cl. D15—8)

FIGURE 1 is a front elevational view of a ladder showing my design, the broken lines thereof indicating that same may be of indeterminate length.

FIGURE 2 is a fragmentary sectional view taken along the line 2—2 of FIGURE 1 and enlarged with respect thereto.

FIGURE 3 is a perspective view of the ladder shown in FIGURE 1.

FIGURE 4 is an enlarged fragmentary side view showing the mounting lugs for the rungs or steps of the ladder in greater detail.

I claim:

The ornamental design for a ladder, substantially as shown.
